UNITED STATES PATENT OFFICE.

WILLIAM JAY BARBER, OF HONEOYE FALLS, NEW YORK.

STOVE-LEG.

SPECIFICATION forming part of Letters Patent No. 654,776, dated July 31, 1900.

Application filed May 2, 1900. Serial No. 15,247. (No model.)

To all whom it may concern:

Be it known that I, WILLIAM JAY BARBER, a citizen of the United States, residing at Honeoye Falls, in the county of Monroe and State of New York, have invented a new and useful Stove-Leg, of which the following is a specification.

The invention relates to improvements in stove-legs.

10 The object of the present invention is to improve the construction of that class of stove-legs which are provided with casters and to provide a simple and comparatively inexpensive one which will be strong and durable and which will be adapted to be readily operated to arrange the caster in position for use, so that the stove may be readily moved, and to cause the stove to rest upon its legs after it has been properly arranged 20 and adjusted.

The invention consists in the construction and novel combination and arrangement of parts hereinafter fully described, illustrated in the accompanying drawings, and pointed 25 out in the claims hereto appended.

In the drawings, Figure 1 is a vertical sectional view of a stove-leg constructed in accordance with this invention, the caster being out of operation. Fig. 2 is a similar view, 30 the caster being in position for use. Fig. 3 is a rear elevation, the parts being arranged as shown in Fig. 1.

Like numerals of reference designate corresponding parts in all the figures of the drawings.

35 I designates a stove-leg provided at its lower portion with bearings 2 and 3, extending horizontally from the inner face of the front portion of the leg and provided with 40 vertically-aligned bearing-openings for the reception of a vertical caster-stem 4, which has its lower end curved and bifurcated to receive a caster-wheel 5. The caster-wheel 5 is mounted on a suitable pivot, and when the 45 leg rests upon the supporting-surface, as illustrated in Figs. 1 and 3 of the accompanying drawings, the caster-wheel is held clear of the floor by means of a tapering coiled spring 6, disposed on a tapering upper portion 7 of the stem, as clearly shown in Fig. 1. The stem 4 of the caster is provided at the

upper end of the tapered portion with a head or enlargement 8, and the coiled spring, which is forced over the head or enlargement 8 in placing it in position, is interposed between 55 the same and the upper one of the lower bearings and is adapted to be compressed, as shown in Fig. 2, when the leg is elevated to throw the weight of the stove upon the 60 caster-wheel 5.

The head or enlargement 8, which has a horizontal upper face, is provided at the center thereof with a concavity 9, in which is seated an antifriction-ball 10, arranged to be engaged by a cam or eccentric lever 11, whereby the latter is adapted to operate freely and frictionlessly; but the antifriction-ball may be omitted, if desired. The cam or eccentric lever consists of a circular head 12 and an arm or body portion 13, extending from 70 the head and forming a handle and adapted to be swung upward and downward from the position shown in Fig. 1 to that illustrated in Fig. 2, and vice versa. The circular head 12 is provided with eccentrically-arranged laterally-extending pivots or trunnions 14, which are received within bearing-recesses 15 of bearings 16, which extend rearward from the inner face of the upper portion of the leg 1. As the lever is oscillated the cam formed 75 by the eccentrically-pivoted head forces the 80 caster-wheel against the floor or other supporting-surface and raises the leg when the said lever is swung downward, and a reverse movement of the lever lowers the leg to the 85 floor. The end 17 of the lever is beveled to fit the upper portion of the leg when it is 90 swung upward against the same. The bearing-recesses 15 of the ears or bearings 16 extend upward from the lower edge thereof, 95 and the pivots or trunnions of the lever are retained therein by the coiled spring and by the weight of the stove. Should the leg be lifted, the spring will retain the trunnions or pivots in the open bearing-recesses and will 100 prevent the ball from escaping. The ball is adapted to rotate in the concavity as the lever is oscillated. The arm or body portion of the lever when swung downward to the position shown in Fig. 2 rests against the end 100 of the bearing 2, and there is no liability of the lever accidentally slipping. The ball also

facilitates the rotary movement of the stem in the vertically-aligned bearings and permits the lower end of the stem to swing freely in any direction.

5. It will be seen that the caster is simple and comparatively inexpensive in construction, that the parts are readily assembled, and that they are capable of being easily operated to bring the caster into position for use and to 10 cause the leg to rest upon the supporting-surface.

What is claimed is—

1. In a device of the class described, the combination with a stove-leg having lower 15 vertically-aligned bearings and provided with upper bearings having recesses at their lower edges, a caster-stem arranged in the vertically-aligned bearings, a lever having pivots or trunnions arranged in the upper bearing-recesses, and a spring engaging the stem and 20 adapted to retain the pivots or trunnions of the lever in the bearing-recesses, substantially as described.

2. In a device of the class described, the 25 combination with a leg provided with upper and lower bearings, the upper bearings being open, a caster-stem removably arranged in the lower bearings and provided with a caster-wheel, a lever detachably mounted in 30 the upper bearings, and a spring engaging the caster-stem and retaining the same and

the lever in the said bearings, substantially as described.

3. In a device of the class described, the combination with a leg provided with lower 35 and upper bearings, a caster-stem arranged in the lower bearings and having a tapered upper portion, and provided at the top thereof with a head, a lever mounted in the upper bearings, and a tapering spring arranged on 40 the tapered portion of the stem and engaging the head thereof and the lower bearing and retaining the said stem in the said bearings, substantially as described.

4. In a device of the class described, the 45 combination with a leg having upper and lower bearings, a stem mounted in the lower bearing and provided at its top with a concavity, a lever mounted in the upper bearing, a ball arranged in the concavity and 50 bearing against the said lever, and a spring engaging the stem and retaining the ball in contact with the lever, substantially as described.

In testimony that I claim the foregoing as 55 my own I have hereto affixed my signature in the presence of two witnesses.

WILLIAM JAY BARBER.
